UNITED STATES PATENT OFFICE.

BURTON C. VAN EMON, OF SAN FRANCISCO, AND WILFRED A. WOLF, OF ALAMEDA, CALIFORNIA.

SAFETY LOCK FOR ELEVATOR DOORS.

1,421,043.

Specification of Letters Patent. Patented June 27, 1922.

Application filed October 25, 1920. Serial No. 419,505.

To all whom it may concern:

Be it known that BURTON C. VAN EMON and WILFRED A. WOLF, citizens of the United States of America, residing at San Francisco and Alameda, respectively, in the county of San Francisco and Alameda and State of California, have invented certain new and useful Improvements in Safety Locks for Elevator Doors, of which the following is a specification.

The present invention relates to safety door locks for automatic elevators and more particularly to that type of lock in which a guard element is used to prevent the release of the latch on the elevator door until the elevator has come to a full stop at a predetermined floor.

In devices of this character, now in use, the guard releasing mechanism is usually controlled by cams or other obstructions attached to the car and adapted to travel therewith or fixed to the shaft and arranged to project into the path of travel of the car.

The primary object of our invention is to dispense with cams on the car and with contacting mechanism in the path of travel of the car.

Another object is to increase the factor of safety in automatic elevators by providing an electrically controlled guard mechanism in which both ends of the controlling circuit are open at all times except when the elevator reaches the predetermined stopping point and in which all danger from grounding the circuit is eliminated.

In our device hereinafter described, we eliminate all trips, cams, and the like from the path of travel and substitute therefor a circular cam wheel geared to or suitably driven by the drum shaft and the entire mechanism is easily coordinated with and attached to conventional elevator apparatus.

In this specification and the annexed drawings, the invention is illustrated in the form considered to be the best, but it is to be understood that the invention is not limited to such form, because it may be embodied in other forms and it is also to be understood that in and by claims following the description it is desired to cover the invention in whatever form it may be embodied.

In the accompanying two sheets of drawings,

Fig. 1 is an elevation of a cam wheel and 55 a disc for supporting fixed contacts in relation thereto.

Fig. 2 is a central vertical cross section of Fig. 1.

Fig. 3 is a central cross section of our lock 60 showing the actuating mechanism controlling the latch guard.

Fig. 4 is a section of same on the line IV—IV of Fig. 3.

Fig. 5 is a fragmentary section of a switch 65 board showing a switch adapted to be actuated by the direction switch of an elevator.

Fig. 6 is a central cross section on a line VI—VI of Fig. 7.

Fig. 7 is a side elevation of a dash pot 70 controlled by a solenoid for introducing a time element and resistance cut in a circuit.

Fig. 8 is a diagram of the wiring in our invention.

In the present embodiment of our invention the numeral 1, Fig. 3, indicates a casing of any suitable shape here shown as rectangular which is adapted to be fitted in place on a door frame and contain the lock mechanism hereinafter described.

The casing 1 is provided with the usual opening 2 through which the hook end of a latch 3 may enter for engagement of the door with the lock. The latch 3 is pivoted to the door as indicated at 4.

Pivoted at 6 is an elbow lever, the lower member 7 of which serves as a guard to secure the latch 3, when in locked position, as shown in Fig. 3. The other member 8 of the lever serves as an armature and is 90 adapted to be actuated by an electromagnet 9 fed by wires 11 and 12. When the magnet 9 is energized the elbow lever is drawn to the dotted position shown in Fig. 3 and the latch 3 is free to disengage from the casing 1. 95

The lock is provided with the usual door switch to prevent operation of the car when a door is open. A lever 13, pivoted at 14 and provided with an integral weighted portion 16, normally hangs in the dotted position shown in Fig. 3, but the added weight of the hook end of the latch 3 depresses the lever to the full line position and causes a metal contact plate 17 to complete a circuit between terminals 18 and 19. It will 100 be seen from the wiring diagram (Fig. 8) that the car cannot be operated when this circuit is open.

In Figs. 1 and 2 we show a mechanism for coordinating the electric lock control with a conventional floor stop device.

Angle irons 21 and 22 are secured as by 5 rivets 23 to an inverted channel iron 24 to form a base to which is secured a standard arm 26 bored to receive a shaft 27 which may be the operating shaft of a floor stop device or may be suitably geared thereto or driven 10 thereby.

Secured to the standard 26 in fixed relation thereto, as indicated by set screw 28, is a disc 29. Radially disposed on the periphery of this fixed disc are make and break 15 contacts in number corresponding to the number of floors served by the elevator and here shown at A B and C.

Keyed as shown at 31 to the shaft 27 is a cam disc 32 adapted to close the circuit by 20 making contact successively at A B and C when turned in either direction by the floor stop device.

The make and break contacts are all alike and but one will be described. A U-shaped 25 member 33 is adapted to straddle the periphery of the disc 29 and is secured thereto by set screws 35. Secured to said member 33 as by screw 34 is a piece of insulative material 36, to which is secured a metal plate 30 form 38 having upstanding lugs 39, 41, through which said lugs extends a pintle pin 42. On this pin is pivoted an elbow lever 43 of conductive material. One end 35 of the said elbow lever is adapted to contact with a spring pressed carbon 44 supported by the platform 38.

The platform 38 is provided with terminals 46, 47, to which the wires of the circuit which it is desired to make and break 40 are secured.

The lower end of lever 43 is turned down to form a shaft for a roller 48 of insulative material, and of a diameter slightly less than the width of the cam track 49 of wheel 45 32. The said wheel has a cam segment as shown at 51 adapted to raise and lower the wheel 48 by contacting on alternate sides thereof during the travel of the cam portion of the track past the fixed wheel, and by so 50 doing make and break contact between terminals 46 and 47.

By referring to Fig. 8 it will be seen that the circuit controlling the magnet in our lock is governed by the direction switch, 55 here shown diagrammatically at 52 and 53 to indicate respectively the upward and downward movement of the car. In our device the direction switch opens the feed circuit and demagnetizes all locks. This is accomplished by the device shown in Fig. 5 in which a fragment 54 of the switchboard is shown. Terminals 56, 57 secure angle pieces 58, 59 of conductive material to the board 54. These terminals are normally connected 60 through a contact plate 61 which is held in

contact with said terminals by an expansion spring 62 in a plug 63. A push contact 64 of insulative material is pushed toward the switch board as the direction switch is closed. We provide an apparatus such as 70 shown in Fig. 5 for both switches so that the circuit is broken when the car is started in either direction.

In order to preclude the possibility of overheating the magnet 9 and to keep a small 75 amount of current in the magnet when the car is idle we provide an automatically operated time element which short circuits resistance when the car stops and circuit is closed between 58 and 59. 80

In Figs. 6 and 7 this device is shown on the switch-board 54. Secured to the said board by a U-bolt is a tubular housing 67, closed at the top by a cover 68. An electromagnet 69 is within the housing. The core 85 71 of the magnet is centrally bored at 72 for entrance of a pin 73 loosely secured as by a pin 74 to the core 71.

The pin 73 is rigidly secured to a plunger 76 loosely fitting within the housing 67. 90 When the magnet 69 is energized the apparatus is in the position shown in Figs. 6 and 7. If the magnet is de-energized the core and plunger drop by gravity to the dotted position. 95

Terminals 77, 78 extend through the switchboard 54. On the back of the board these terminals are connected by a suitable conductor which has approximately 3000 ohms resistance as indicated at 79, while on the face of the board, the terminals are provided with metal clips 81, 82. Contact is made between these clips and the terminals 77, 78 by a metal band 83 surrounding an insulation disc 84 secured to the core 71 by a screw 86. 100

It results from this structure that when the car stops full current is sent to the coil in the lock giving it full strength to open the guard and release the latch. The 110 plunger 76 slowly settles while displacing air in the housing 67, breaking the direct current and sending same through resistance element 79, allowing a small current to pass and hold guard open all the time the car is at rest. If a ground should occur on circuit to coil in lock the resistance is so high that the guard would not lift to release the door latch. 115

The operation of an elevator equipped with our device is as follows: When the car is at rest at a floor, both direction switches 52, 53, are out, which closes the feed circuit to locks. 120

Return circuit is closed by contact on floor stop device for this particular floor. When button is pressed, the direction switch (either up or down) goes in, opening feed circuit to locks, and the keeper 7 will drop and the door is locked before the car starts. 125 130

There is no current flowing to the lock when the car is in motion. When the car stops at a floor, circuit is made to that lock and no other. The full force of current energizes 5 the magnet and releases the latch.

Having thus described our invention, what we claim as new and desire to protect by Letters Patent of the U. S. is—

1. In an electrical apparatus for controlling an elevator door lock, an electromagnet, a latch, a guard for said latch, an armature adapted to operate said guard when actuated by said magnet, means for energizing said magnet when the elevator reaches a pre-determined position, and means for maintaining a relatively small amount of energy in said magnet while the elevator is at rest to retain the lock in inoperative position. 10
2. In an electrical apparatus for controlling an elevator door lock, an electromagnet, a latch, a guard for said latch, an armature adapted to operate said guard when actuated by said magnet, means for energizing 15

said magnet when the elevator reaches a pre-determined position, means for maintaining a relatively small amount of energy in 25 said magnet while the elevator is at rest to retain the guard in inoperative position and means coordinated with the starting mechanism of said elevator for deenergizing said magnet to operate the guard. 30

3. An electrically operated device for locking a latch to a lock housing comprising an electromagnet secured to said housing, a latch, a guard for said latch, a lever normally locking said latch to said lock housing and adapted to release said latch when said magnet is energized, means for energizing said magnet and means for automatically reducing the energy in said magnet to 35 a quantity sufficient to hold said lever in 40 inoperative position.

In testimony whereof we affix our signatures.

BURTON C. VAN EMON.
WILFRED A. WOLF.
